UNITED STATES PATENT OFFICE.

DAVID C. PAYNE, OF ELKHART, INDIANA.

IMPROVEMENT IN GRUBBING-MACHINES.

Specification forming part of Letters Patent No. 36,022, dated July 29, 1862.

To all whom it may concern:

Be it known that I, DAVID C. PAYNE, of Elkhart, in the county of Elkhart and State of Indiana, have invented a new and Improved Grubbing-Machine; and I do hereby declare that the following is a full, clear, and exact description of the same, reference being had to the accompanying drawings, making a part of this specification, in which—

Figure 1 is a side elevation of my improved machine (shown in red) in position for pulling a grub or stump. Fig. 2 is a plan of the same.

Similar letters of reference indicate corresponding parts in the two figures.

The object of this invention is to obtain a light, simple, and inexpensive machine for pulling or extracting grubs and stumps from the earth in clearing new land; and it consists in a peculiar device for automatically locking and unlocking the wheels of the machine at the proper moment, the former to cause the wheels, in connection with the axle, to form the fulcrum of the lever, and the latter to allow the machine to be used for transporting the grub or stump from the field, as will be hereinafter fully explained.

To enable others skilled in the art to fully understand and use my invention I will proceed to describe its construction and operation.

A represents a long lever, which may be made of a single piece of timber, or of several thin pieces united together by glue or in any other suitable manner. This lever is supported near its back end on top and in the middle of an axle, B, which is crooked from the inside of the journals or gudgeons on which the wheels C C' are loosely fitted, the top side of the axle being its convex surface. The axle B, which is in curved form inside of its journals, is designed to be cast hollow, of cast or malleable iron, with a flange on two opposite sides, to which flanges the lever is secured by bolts which pass vertically through the lever and flanges and have nuts screwed on their lower ends. Attached to the top side of the lever at the back end, and extending equally over each side of the axle, is a metal plate for strengthening that end of the lever, and also furnishing an unyielding seat for the bite D,

which rests on the plate at the extreme end of the lever, and is firmly secured thereto by one or more bolts passing through it and the lever and fastened by nuts on the under side. Attached concentrically to the inner sides of the wheels C C' are annular toothed rims D D', the teeth of said rims being on their outer periphery. Arranged on the under side of the lever in front of the annular toothed rims is a lock-bar, E, which is provided with a central arm, a, and fitted to have longitudinal movement in stirrups b b, the arms sliding in staples or clips c c. The lock-bar E extends on each side of the lever a distance equal or nearly equal to that of the back sides of the annular toothed rims from the middle of the axle. The end of the arm a of the lock-bar E terminates in a straight hook, which projects to one side of the lever and in front of a weight, F, which is attached to the side of the lever by a pivot, which allows the weight to always retain its vertical position without regard to the position of the lever.

H is a U-shaped clevis of about one-third (more or less) greater width than the lever, and bent at its ends in hook form, so as to catch over the axle. In the middle of the bend of the clevis on the inside is a smooth space, and on each side of it a feathered or knife edge, the former to hold the clevis in a central position, while the latter bury themselves in the surface of the wood.

The operation is as follows: The machine being first backed up to the grub or stump to be pulled, the lever is turned up in a position shown in red in Fig. 1, the bite resting against the grub close to the ground, and the lock-bar resting in the teeth of the annular toothed rims, and thereby locking the wheels and lever together. The clevis is then put around or over the grub accordingly as the tree is standing or cut down, and hooked over the axle. The power to pull the grub or stump is applied to the upper end of the lever in the usual manner. As the lever descends at its front end in the act of pulling the grub or stump from the earth, the wheels, being locked to the lever, move simultaneously therewith and correspondingly advance until the lever attains a horizontal position, when the weight, pressing against the straight hook of the arm, with-

draws the lock-bar from the teeth of the annular rims, and thus leaves the wheels free to turn independently upon their axles, whereby the machine is adapted to use in transporting the grub or stump in the machine from the field. The crooked axle forms a very firm and unyielding fulcrum for the lever, and also serves to apply the power thereof more direct to the grub in extracting it from the ground than with the straight axle. I am aware that pivoted pawls or braces have been used in connection with annular toothed rims for locking together the wheels and lever of a grubbing-machine, and do not wish to be understood as claiming such; but,

Having described my invention, what I do claim, and desire to secure by Letters Patent, is—

The lever A, lock-bar E, hooked arm *a*, and weight F, with the annular toothed rims D D', wheels C C', and crooked axle B, when combined and arranged to operate in the manner and for the purpose set forth.

D. C. PAYNE.
